UNITED STATES PATENT OFFICE.

SAMUEL GARRETT AND WILLIAM P. LAYTON, OF CHICAGO, ILLINOIS, ASSIGNEES TO GARRETT-GO-CART AND CARRIAGE COMPANY, OF CHICAGO, ILLINOIS, A CORPORATION OF ILLINOIS.

CONVERTIBLE BABY-CARRIAGE AND BASSINET.

Application filed February 11, 1921. Serial No. 444,096.

To all whom it may concern:

Be it known that we, SAMUEL GARRETT and WILLIAM P. LAYTON, citizens of the United States, residing at Chicago, in the county of Cook and State of Illinois, have invented certain new and useful Improvements in Convertible Baby Carriages and Bassinets, of which the following is a specification.

10 The invention relates to baby carriages in which the body is removable and may be separately used as a bassinet.

Much inconvenience attends the use of the ordinary construction of baby carriages by 15 reason of the frequent necessity for moving the carriage up and down stairways between living apartments and the street. Moving the carriage upon a stairway requires a considerable effort, and severely strains the 20 structure of the carriage by its bumping progress over the stairs. It is also objectionable in the home because of dirt from the street frequently adhering to the wheels.

A further difficulty is the general prohibition 25 of baby carriages from the halls and stairways of apartment buildings and from other public places, resulting in the necessity for leaving the carriage at the building entrance or in a basement, and carrying the 30 child occupant about in the arms.

It is the object of our invention to provide a baby carriage having a readily removable bassinet body which may be conveniently slung upon the arm and carried about independently of the running gear and 35 hood, and which is equipped with folding legs adapted to support the body in its separate use as a bassinet.

The invention contemplates great convenience 40 in its provision for the separate use of the bassinet body. Without disturbing the occupant, the body may be carried into a home and there readily set up for use in the ordinary manner of a bassinet.

45 A frequent problem is the comfortable disposition of a small child being taken out for a drive in an automobile. The separate bassinet body is particularly suitable for such use, in that the body may be set up on its supporting legs within the tonneau of the car, providing a comfortable and convenient berth for the child without burdening the other occupants of the automobile.

Another object of the invention is to pro-

vide simple, quickly releasable means for securing the body upon its running gear which may be readily operated from a convenient position.

A further object is to provide means operable by one hand for swinging the folding legs into supporting position and for positively securing them in that position when the body is in use as a bassinet.

The detailed construction and arrangement by which we attain these objects are set out in the following description, and illustrated in the accompanying drawings, of a preferred embodiment of our invention. It is to be understood, however, that in the interpretation of the appended claims they are not to be limited to the precise construction or arrangement set forth, except as may be necessitated by the state of the prior art.

In the drawings Figure 1 is a view of the carriage with the removable body mounted on the running gear, and partially in section to show the means of support. Fig. 2 is a plan view of the running gear alone. Fig. 3 is an end elevation of the bassinet body separately set up upon its supporting legs. Fig. 4 is a plan view of the body. Figs. 5, 6 and 7 are detail views of our fastening device for securing the body to the carriage frame, the Fig. 7 being a sectional view taken on the line 7-7 in Fig. 6. Figs. 8 and 9 represent a fastening means for securing the body legs in supporting position. Figs. 10, 11, 12 and 13 illustrate our preferred construction of means for operating and securing in position the supporting legs for the body.

Referring to Fig. 1, the numeral 1 indicates a pair of parallel spaced side bars of a carriage frame, the bars extending rearwardly and upwardly to support a handle 2. A front axle 3 and a rear axle 4 are suitably secured to the side bars 1, and carry a pair of front wheels 5, and a pair of rear wheels 6. A pair of front and rear springs 7 and 8, respectively, are secured to each side bar and extend generally upward in suitable curved form to give maximum resiliency. The upper end of each spring pivotally engages a hanger 9 carried by a pair of side members 10 of a skeleton frame arranged for the support of the removable body.

The body 11, constructed in the form of a bassinet, is mounted on a supporting frame of which the side members 12 rest upon cushioning blocks 13 carried by the side members 10 of the spring frame.

The body is secured in position upon the skeleton frame by means of a pair of cross members 14 which are secured to the side members 10 of the spring frame, and carry 10 a pair of upright supports 15 at each side of the body. The supports 15 are reversely curved and rigidly joined at their mid-sections 16, the upper ends of each pair diverging from the joint 16 and supporting at their 15 upper extremities a looped band 17 rigidly secured to the supports and extending outwardly from the body. A swinging hood 18 is supported at each side by an arm 19 pivotally attached to the outer portion of 20 the band 17 by means of an adjustable clamping device 20. A bent strap 21, secured to the arm 19, limits the swinging movement of the hood 18 by engagement with the band 17.

25 Mounted on each side of the body 11 and positioned oppositely to the upper divergent portions of the supports 15, is an angular plate 22 having a horizontal portion 23 extending between the diverging ends of the supports 15. The horizontal portion 23 is laterally notched to receive the supports 15, and carries at its outer end a downwardly extending flange 24 which engages the outside of the supports 15 and secures the plate 22 against lateral displacement. A strap 25, secured to the joined portions of the supports 15, and extending upwardly through the positioning staple 26, has its upper end 27 bent outwardly to support a locking lever 30. The latter is pivotally mounted on the strap end 27 and carries a tongue 29 which is adapted to be swung over the horizontal portion 23 of the angle plate 22 secured to the body, and thereby lock it in its relation to the supports 15.

35 It will be obvious that with the levers 28 on each side of the body in locking position, the body is securely held in its position on the spring frame, and that by the simple operation of moving the levers 28 into inoperative position on each side of the body the latter may be lifted clear of the frame and removed from the running gear.

The body is supported when separated 40 from the running gear by a pair of folding legs mounted at each end of the body. Each pair comprises an inverted U-shaped member having side leg portions 30 and a connecting bearing portion 31. The latter are rotatably mounted in a pair of strap bearings secured to the ends of the body frame. In our preferred construction, the strap bearings 32 (Figs. 10 and 12) are secured to the end member 33 of the frame. They 45 may, however, be constructed as in Fig. 9,

the bearings 34 therein being shown as secured to the frame member 33 and the lower framing member 35 of the basket woven sides of the body.

In our preferred construction for operating and securing the legs in open position (Figs. 10 to 13 inclusive) a block 36 connects the side member 12 of the frame with the framing member 35, at each side of the body, and rigidly secured thereto is a bearing plate 37. A lever 38 is pivoted at its center upon the plate 37. A pair of connecting links 39 have their inner ends pivotally connected at 40 to the respective ends of the lever 38, and their outer ends 41 pivoted respectively to one of the legs 30, the links being so arranged that the swinging legs may be folded upwardly toward the bottom of the body by the single movement by the operator of one pair or the other.

When the legs are swung downwardly in position to support the body, the lever 38 may be locked against reverse rotative movement by a locking lever 42 pivoted on the plate 37 and having an angularly extending end 43 arranged to engage the lever 38 when the latter is in the position assumed upon opening the folding legs, and thereby prevent the legs being swung toward the body, and providing positive security against the collapse of the supporting legs when the body is being separately used as a bassinet. When in folded position beneath the frame of the body, and the latter placed upon the carriage running gear, the legs are supported upon the outer ends of the cross members 14 which latter are constructed with a double bend 14^a forming a pocket to receive the legs.

A modification of our locking device 105 for the body legs is shown in Figs. 3, 8 and 9 wherein we have employed a pin 44 transversely secured in the bearing portion 31 of the leg members at each end of the body, which upon swinging the legs into their supporting position is carried upwardly to engage a socket 45 in the downwardly bent end of a plate 46 secured to the end member of the body frame. In its movement into engagement with the socket, the pin 44 displaces a snap lock 47 pivoted on the end of the plate 46 and adapted to swing beneath the pin to securely lock it in its position in the socket. The snap lock is actuated by a spring member 48 secured on 110 the end member of the body frame.

For conveniently lifting the body from the running gear we have provided a hand strap 49 having bifurcated ends 50 secured in spaced relation at each side of the upper 125 edge of the body 11. The strap is so arranged that a person may place his arm beneath the strap and thereby lift the body free of the running gear with one arm, having the other arm and hand free to manipu- 130

late the body fastening devices and to swing the supporting legs into operative position.

A supplemental hood 51 may be carried upon bows pivotally secured upon the sides 5 of the body as at 52, and adapted to be raised as desired to enclose and protect either end of the body.

We claim as our invention:

1. A baby carriage comprising a running gear, a removable body supported upon the running gear, and means for detachably fastening the sides of the body to the running gear whereby to hold the body against lateral displacement thereon.

15 2. A baby carriage comprising a running gear, a removable body supported by the running gear, and means for detachably fastening the sides of the body to the running gear, said body being provided with 20 supports normally folded in inoperative position and operatively connected so as to be simultaneously movable to operative position when the body is removed from the running gear.

25 3. In a baby carriage having a running gear, a removable body adapted to rest on the running gear, a plurality of upright supports mounted on the running gear and adapted to carry a hood, and means mounted 30 on said supports and on the adjacent sides of said body adapted to be selectively operated to secure said body to said running gear or to permit the removal of said body.

4. In a baby carriage having a running gear and a removable body, means for detachably securing the body to the running gear comprising a support mounted on the running gear and extending adjacent to the side of the body, said support having a bifurcated upper end, a member mounted on said body adapted to engage the bifurcated end of said support, and means for locking said support and said member in such engagement.

45 5. A baby carriage having a running gear, a removable body, and a hood permanently mounted on said running gear free from said body.

6. In a baby carriage having a running gear, a removable body, and a hood, the combination of a pair of supports extending upwardly from opposite sides of said running gear adjacent the sides of said body, each of said supports having an upwardly opening recess at its upper end, a horizontally looped band having its spaced ends secured to the support on opposite sides of said recess, an arm pivotally mounted on the outer portion of said band and adapted to carry one side 55 of the hood, and a member mounted on said body having an outwardly extending portion adapted to engage said recess and thereby secure said body against lateral movement.

65 7. In a baby carriage having a running

gear, and a removable body, the combination of a support extending upwardly from each of opposite sides of the running gear adjacent to the sides of said body and having a recess in its upper end, a member mounted 70 on said body having a laterally extending portion adapted to enter said recess with the replacement of the body upon the running gear and having interlocking engagement with the marginal sides of said support, and a locking lever pivotally mounted on said support and adapted to be swung into engagement with said member to prevent its disengagement from said recess.

10 8. A baby carriage having a running gear, a removable body normally supported by the running gear, and means for supporting the body independently of the carriage, said means comprising a plurality of operatively connected legs movable simultaneously 85 to operative and non-operative positions.

9. In a baby carriage having a running gear and a removable body, means for detachably fastening the body to the running gear comprising a vertically extending support mounted on the running gear adjacent the side of the body, said support having its upper end recessed, and a member mounted on the side of said body adapted 90 to engage the recessed end of said support.

10 10. In a baby carriage, the combination with a removable body, of a pair of supporting members each having a horizontal portion and a pair of depending leg portions rigid therewith, bearings mounted on opposite sides of said body and rotatably supporting the horizontal portions of said members, and linkage connecting the opposite leg portions of said members and constraining said members to move simultaneously 105 into position to support the body or into inoperative position beneath the body.

11. In a baby carriage having a removable body, the combination of a pair of supporting legs swingably mounted on opposite 110 sides of the body, a lever centrally pivoted on said body, and a pair of links pivotally connected to the opposite ends of said lever and to one each of said legs, whereby the movement of one of said legs operates to similarly move the other of said legs.

12. In a baby carriage having a removable body, the combination of a pair of supporting legs swingably mounted on opposite sides of the body, a lever centrally pivoted 120 on said body, a pair of links pivotally connected to the opposite ends of said lever and to one each of said legs, and a pivoted locking bar mounted on said body and adapted to engage the said lever to prevent 125 its rotative movement, thereby locking said legs in rigid position.

13. In a baby carriage having a removable body, means for removing said body in normal position and comprising a strap having 130

bifurcated ends, the separable portions of each of said ends being adapted to be attached to one side of said body in equidistant opposite relation to its center of gravity.

5 14. In a baby carriage having a running gear and a removable body, the combination of cushion blocks carried by the running gear on which said body normally rests, and a support extending upwardly from each of
10 opposite sides of the running gear adjacent to the sides of said body and having a recess in its upper end, a member mounted on said body adapted to enter said recess so as to hold the body against lateral displacement
15 upon the cushion blocks.

15. In a baby carriage, the combination with a running gear and a removable body of a support extending upwardly from each

of opposite sides of the running gear adjacent the sides of the body and each comprising a pair of double curved bars having their lower ends fastened to the running gear and their middle portions fastened together with their upper end portions diverging to form a recess, corresponding angular members 25 fastened to said body, each having an outstanding leg notched to permit entrance to said recess, and a lever pivotally mounted on the support operable to engage said outstanding leg to lock said angular member and 30 body against lateral movement relative to said running gear.

In testimony whereof we have hereunto set our hands.

SAMUEL GARRETT.
WILLIAM P. LAYTON.
